COMBINED BRASSIERE AND MIDRIFF CINCER

Lee R. Smith, Montclair, N.J., assignor to Lido Foundations International, Inc., New York, N.Y.

Filed Mar. 20, 1975, Ser. No. 560,484

Term of patent 14 years

Int. Cl. D2—01

U.S. Cl. D2—24

FIG. 1

FIG. 2

FIG. 3

FIG. 1 is a front elevational view of a combined brassiere and midriff cincher showing my new design;

FIG. 2 is a rear elevational view; and

FIG. 3 is a front perspective view.

I claim:

The ornamental design for a combined brassiere and midriff cincher, as shown.
